AUTOMATIC FIRE EXTINGUISHER

Filed Dec. 5, 1927

UNITED STATES PATENT OFFICE

HOWARD W. PARTLOW, OF UTICA, NEW YORK

AUTOMATIC FIRE EXTINGUISHER

Application filed December 5, 1927. Serial No. 237,888.

This invention relates to an automatic control for fire extinguishers, especially of the class employed for protecting dipping-tanks, varnish kettles, cleaning tubs, and the like, wherein the solutions are separately held in containers of the tumbler type, which gravitate when released and assume the mixing and discharging position.

The object of the invention is to provide novel means for holding the tumbler inactive, the said holding means consisting of a train of separable levers, which are usually mounted adjacent the tumbler, and a latch carried by the tumbler, which is arranged to engage one of the levers. A further object is to provide complementary thermostats for controlling said holding parts, comprising primary and secondary members, one of said members being inclosed by the other, and being connected to the primary lever of said train, and the arrangement of said members being such that, as long as the temperature in the vicinity of the extinguishing unit remains normal, or rises at a normal rate, the tumbler is held inactive, and during such periods both the primary and secondary thermostats tend to neutralize each other and prevent accidental or untimely release of the tumbler. On the other hand, when the temperature rises quickly, or at an abnormal rate, as by the starting of a fire adjacent the tumbler, the sudden rise of temperature causes the exposed primary member to expand and move the secondary member in the direction for disconnecting the said levers, and releasing and enabling the tumbler, to rotate towards the discharge position by its own weight. And a further object is to provide automatic holding and releasing means for fire extinguishers of the class, in which compressed air, electricity or other more or less uncertain and intangible elements heretofore employed are eliminated, and to substitute therefor an extremely simple and direct thermal-mechanical controlling mechanism.

The various features and parts of the invention will be understood from the detailed description which follows, and by reference to the accompanying drawings, in which—

50 Figure 1 is an end elevation of the extin-

guishing unit, to which my improvement is applied. Fig. 2 is a side elevation of the same. Fig. 3 is an enlarged front side elevation of the thermal-mechanical control. Fig. 4 is an end elevation of the same. And Fig. 5 is a top plan view of the tumbler held inactive by the control.

Referring to Figs. 1, 2 and 5 of the drawing, the fire extinguishing unit comprises an upright frame 2, in which is hung eccentrically a cylindrical tumbler or container 3, the latter preferably being divided interiorly into noncommunicating compartments 3'—3^a, which hold separately the solutions that when combined produces the fire quenching fluid. 4 represents a manifold which is mounted externally near the top of the tumbler, and is formed with a common chamber that communicates with the compartments 3'—3^a, and wherein the solutions become mixed when the tumbler is rotated to the discharge position, shown in Fig. 1, in which the short arrow indicates the point at which the discharge of the contents takes place. The frame 2 is provided with flange feet 2', by which the unit may be fastened to a floor or shelf when in the upright position, shown in the drawing. When the extinguishing unit is used to protect dip tanks and the like, the tumbler 3 is usually supported from the ceiling, and for this purpose the top 2^a of the frame is provided with a swivel-loop, as 2^b, to which a chain, hook or other suspending means may be attached.

My automatic control for the extinguishing unit comprises an elongated body 5, which may be mounted on a bracket 5', the said bracket being secured to an upright 2^c of the frame 2. The top end of the body 5 has a slot, as 5^a, to receive a rockable lever 6, which is pivoted by a pin 6'. One end of the lever 6 overlaps the tumbler 3, and is arranged to be engaged by a latch carried by the tumbler, for holding the latter inactive, as shown in Figs. 1, 2 and 5. The free end of the latch 7 is formed with a long arm 7' and a short arm 7^a, which are arranged in a common plane and spaced from each other and from the tumbler, the arm 7^a being arranged to engage the underside of the lever 6 for

holding the tumbler from rotating clock-wise, as shown by the long arrow in Fig. 1. The arm 7' of the latch is employed for rocking the lever 6 from the oblique or released position, to the horizontal or holding position, as shown in Figs. 1 and 2, by the reverse clock-wise rotation of the tumbler. The opposite end of lever 6 is arranged to overlap the free end of an upright lever 8, when the parts are set for holding the tumbler from acting. The lower end of lever 8 is pivoted to a post 8', which is supported by the body 5. A spring 8^a tends to resiliently maintain lever 8 in the holding position. The levers 6 and 8 are controlled by a thermostat comprising complementary members as 9—9', the latter member telescoping the former and being reciprocatable therein to a certain extent, and also being connected to the lever 8. The members 9—9' preferably consist of relatively thin brass tubing, and are of substantially equal expansibility. The outer tube 9 is preferably perforated, as at 9^a, for enabling the smaller tube 9' to expand with tube 9, when the temperature is normal, or rises at a normal rate. One end of tube 9 is preferably rigidly secured to the body 5, its opposite end being loosely supported by a bracket 10, which is rigid to an upright 2^a of the frame. One end of the tube 9' preferably passes loosely through the body 5 and is pivoted to the shorter end of the lever 8. The opposite end of tube 9' preferably extends beyond the free end of tube 9, and is threaded and fitted with nuts 12, which normally engage the end of tube 9, and afford means for adjusting the lever 8 relatively to the lever 6, as may be understood by consulting Figs. 1 and 3. By this arrangement, when tube 9 expands, as by any abnormal rise of temperature, the said tube lengthens, and exerts pressure against nuts 12, which moves the tube 9' axially and swings lever 8 away from lever 6, which enables the eccentrically hung tumbler to effect its release by tilting lever 6, as shown in Figs. 1 and 3. This quick expansion of tube 9 occurs before the abnormal heat has had time to penetrate tube 9 and effect any appreciable expansion of the tube 9'. When the temperature rises at a normal rate, the tubes 9 and 9' expand or elongate substantially to the same extent and tend to prevent untimely releasing of the tumbler 3, and the consequent waste of the extinguishing fluid.

My improved control is extremely simple, positive and direct in its operation, and is especially adapted for individual or local installation, as herein shown and described.

Having thus described my invention, what I claim is—

1. A latch release mechanism for a fire extinguisher having a tumbler rotatably mounted in a frame and provided with a latch on its periphery, including a vertical member,

means connected to said member and formed for connection to the frame to rigidly support the member adjacent to an end of the frame and in spaced relation to the periphery of the tumbler, a horizontal lever pivoted between its ends to said vertical member and having its inner end lapping the periphery of the tumbler and engageable with the latch of the tumbler, a vertical lever having its upper end underlying and engageable with the under side of the outer end of the horizontal lever, means to pivotally mount said vertical lever, on said vertical member, temperature responsive means connected at one end to the lower end of the vertical lever to actuate the same, and means to support the other end of said temperature responsive means from said frame of the tumbler.

2. A latch release mechanism for a fire extinguisher having a tumbler rotatably mounted in a frame and provided with a latch on its periphery, including a vertical member, means connected to said member and formed for connection to the frame to rigidly support the member adjacent to an end of the frame and in spaced relation to the periphery of the tumbler, a pivoted member on the vertical member formed to engage with the latch, a vertical lever formed to engage with said pivoted member, means to pivotally mount said vertical lever on said vertical member, and temperature responsive means connected to the vertical lever to actuate same.

In testimony whereof I affix my signature.
